US0D1071928S

(12) **United States Design Patent** (10) **Patent No.:** **US D1,071,928 S**
(45) **Date of Patent:** **** Apr. 22, 2025**

(54) **MUTING DEVICE**

(71) Applicant: **MuteMe LLC**, El Dorado Hills, CA (US)

(72) Inventors: **Paramveer Singh Dhoot**, El Dorado Hills, CA (US); **Handeep Kaur**, El Dorado Hills, CA (US); **Tye Davis**, Lincoln, CA (US); **Brittany Davis**, Lincoln, CA (US); **Pavan Purewal**, Lincoln, CA (US)

(73) Assignee: **MuteMe LLC**, El Dorado Hills, CA (US)

(**) Term: **15 Years**

(21) Appl. No.: **29/790,580**

(22) Filed: **Dec. 3, 2021**

(51) LOC (15) Cl. **14-02**

(52) U.S. Cl.

USPC **D14/357**

(58) **Field of Classification Search**

USPC D21/812; D13/184, 149, 107, 273; D14/137, 388, 436, 435.1, 433, 441, 454

CPC ... H01H 13/14; A63F 9/00; A63F 9/18; G06F 3/00; G06F 3/002

CLAIM

The ornamental design for a muting device, as shown and described.

DESCRIPTION

FIG. 1 is a perspective top view of a first embodiment of the muting device in accordance with the new design;

FIG. 2 is a perspective bottom view of the device of FIG. 1;

FIG. 3 is a back view of the device of FIG. 1;

FIG. 4 is a front view of the device of FIG. 1;

FIG. 5 is a right view of the device of FIG. 1;

FIG. 6 is a left view of the device of FIG. 1;

FIG. 7 is a top view of the device of FIG. 1;

FIG. 8 is the bottom view of the device of FIG. 1;

FIG. 9 is a perspective top view of a second embodiment of the muting device in accordance with the new design; and, FIG. 10 is a perspective top view of an embodiment of the muting device in accordance with the new design being connected to a laptop.

The broken line showing of portions of the muting device is included for the purpose of illustrating environmental structure and form no part of the claimed design. The diagonal lines are used to indicate shading and do not depict any particular color or texture.

1 Claim, 5 Drawing Sheets
